UNITED STATES PATENT OFFICE.

HUBERT C. WHITE, OF FULTONVILLE, NEW YORK, ASSIGNOR OF ONE-HALF TO
FRANK S. PORTER, OF JACKSON, MICHIGAN.

DEVICE FOR CRACKING NUTS.

1,049,183.

Specification of Letters Patent. Patented Dec. 31, 1912.

Application filed April 12, 1912. Serial No. 690,237.

To all whom it may concern:

Be it known that I, HUBERT C. WHITE, a citizen of the United States, residing at Fultonville, county of Montgomery, State of New York, have invented a certain new and useful Improvement in Devices for Cracking Nuts, and declare the following to be a full, clear, and exact description of the same, such as will enable others skilled in the art to which it pertains to make and use the same, reference being had to the accompanying drawings, which form a part of this specification.

My invention relates to a device for cracking hard shell nuts and is more particularly designed as an improvement on my invention shown and described in United States Letters Patent No. 1,004,611, dated October 3rd, 1911.

The object of the present invention is to improve the efficiency of the device referred to, to simplify its construction and operation, to reduce the number of parts, and to provide means for automatically interposing a shield adapted to protect the operator against injury from flying fragments of shell during the act of cracking the nut,—the construction being such that the shield is also automatically raised when the device is in position to receive the succeeding nut to be cracked.

A further object of the invention is to increase the leverage afforded by the device over that in the patent referred to, while at the same time reducing the relative size and number of parts.

Other advantages and improvements will hereafter appear.

In the drawings accompanying this specification:—Figure 1 is a perspective view of the device shown in position to receive the nut, with parts broken away that it may be more conveniently placed upon the sheet. Fig. 2 is a longitudinal vertical section showing the parts in the position indicated in Fig. 1. Fig. 3 is a similar longitudinal vertical section with the device in the position occupied when about to crack the nut. Fig. 4 is a cross-sectional view of a detail showing one of the side frames provided with a lug to limit the further downward movement of the lever. Fig. 5 is a detail view of the rock shaft. Fig. 6 is a side ele-

vation of the follower or sliding member. Fig. 7 is an end elevation of the same.

55

Referring to the letters of reference placed upon the drawings indicating the several parts: A denotes a base board provided with an opening A' through which the cracked nuts may fall into a receptacle 60 placed beneath to receive them.

B and B' are the side members of the frame connected together at one end by the cross member B² adapted to receive and support an adjustable thumb-screw C, having 65 a concave end C', to receive the end of the nut to be cracked.

D is a rock shaft journaled in the side walls B and B'.

E is an operating lever secured to the web 70 portion D' of the rock shaft by bolts e and e'.

d is a lug on the opposite end of the rock shaft which serves to prevent the side walls B and B' from spreading when the parts 75 are assembled. Spaced from the lug d and on the inside of the member B is a beaded or rib portion d'. d² is a like beaded portion on the rock shaft adjacent to the inner face of the opposite side wall. These ribs 80 coacting with the side walls B and B' prevent lateral movement of the rock shaft when the parts are assembled.

b is a V-shaped opening in the frame through which the web portion D' of the 85 rock shaft may pass when assembling the parts.

F is a sliding member having lugs f adapted to project into the slotted way b' of the side members which serve to guide the 90 sliding member while reciprocating between the frames B and B'.

F' is an arm integral with the sliding member pivoted between the crank arms d³ of the rock shaft D.

95

As indicated in Figs. 2 and 3, the rock shaft is recessed at d⁴ to receive the end of the arm F' to provide for a relatively great leverage while permitting the sliding member to assume a slightly inclined position, 100 as indicated in Fig. 2, to admit of the more convenient entry of the nut to be cracked between it and the end of the adjustable thumb-screw C.

G is a lug projecting from the side frame 105 B' against which the nut of the bolt e' abuts

to limit the further downward movement of the lever, thus protecting the hand of the operator from injury through violent accidental contact with the base.

5 H is a hinged cover pivoted at h to the arm F' of the sliding member.

h' is a projecting portion of the cover extending beyond its pivot adapted to be acted upon by the cam-shaped face D² of the 10 rock shaft whereby the cover is raised by a tilting movement when the lever is thrown to the position indicated in Fig. 2;—the cover closing by gravity over the end of the nut to be cracked upon being released 15 from the action of the cam when the parts are in the position indicated in Fig. 3.

f' is a depression in the sliding member F to receive the end of the nut to be cracked.

Having indicated the several parts by 20 reference letters, the construction and operation of the device will be readily understood.

To crack a nut, the operating lever E is thrown to the position indicated in Figs. 1 25 and 2, this action raises the cover and forces the sliding member away from the adjustable thumb-screw to the limit of its movement,—the sliding member being slightly inclined to provide for the ready insertion of 30 the nut between it and the end of the adjustable thumb-screw. It will be obvious that the inclination given to the sliding member is in a measure due to forming the rock shaft with a recess or cut away portion d⁴ into which the arm F' may project when the parts are in the position indicated 35 in Figs. 1 and 2. Attention is called to the further advantage obtained by this construction in that the relative leverage is 40 thereby increased.

The thumb-screw being approximately adjusted to receive the nut to be fractured, the latter is placed in position and the lever E operated, gripping the nut between the sliding member and the thumb-screw. The 45 cover H being released from its elevated position through the movement of the cam, closes by gravity over the nut to be cracked as indicated in Fig. 3, to shield the operator 50 from the flying fragments. Upon the nut being cracked through a further movement of the lever, the kernel and fractured portions of the shell fall through the opening A in the base board into a receptacle (not 55 shown) placed beneath the base for their reception.

It will be seen upon referring to Fig. 2 that when the device is in an open position the end of the sliding member is inclined to 60 provide for the ready insertion of the nut between it and the thumb-screw, as before explained;—and on referring to Fig. 3, it will be observed that the end wall of the sliding member assumes a vertical position 65 as it approaches the adjustable thumb-screw,

whereby the nut to be cracked is firmly held between it and the thumb-screw in such manner as to afford an equal crushing pressure upon the ends of the nut, thus insuring the shell being fractured so as to release the 70 kernel without injuring the latter.

Having thus described my invention, what I claim is:—

1. In a device of the character described, a frame slotted to receive a sliding element supported therein, a rock shaft journaled in the frame, a lever for operating the rock shaft, the slideable element provided with a rearwardly projecting arm pivoted to the rock shaft, an adjustable abutment between 75 which and the sliding element the nut to be fractured is placed, a tilting cover bridging the space between the sliding element and the abutment, and means whereby the cover is automatically tilted and raised to 80 admit of the nut being placed between the sliding element and the abutment upon operating the lever in one direction, the cover being released from its elevated position that it may descend to confine the fragments 85 of the fractured shell upon operating the lever in the opposite direction.

2. In a device of the character described, a frame having ways adapted to guide a sliding element, a rock shaft journaled in 90 the frame, means for operating the rock shaft, the slideable element provided with a projecting arm pivoted to the rock shaft, an adjustable abutment between which and the sliding element the nut to be fractured is 95 placed, a tilting cover bridging the space between the sliding element and abutment and pivoted to the sliding element, and means consisting of a cam-shaped face carried by said rock shaft adapted to tilt said 100 cover when the rock shaft is operated in one direction and to release the cover whereby it may close and bridge the space between the sliding element and abutment upon operating the rock shaft in the opposite direction.

3. In a device of the character described, a pair of side frames provided with ways to receive and guide a sliding element supported therein, an adjustable abutment, the 115 slideable element adapted to reciprocate toward and away from the adjustable abutment, said slideable element provided with a projecting arm, a rock shaft journaled in the side frames having a transverse recess 120 into which the arm of the sliding element is adapted to project, said rock shaft provided with an arm pivoted to the projecting arm of the sliding element to actuate the latter, and means for operating the rock shaft.

4. In a device of the character described, a frame provided with ways to support and guide a slideable element, an adjustable abutment supported in said frame, the slideable element having a rearwardly extending arm 130

integral therewith, a rock shaft journaled in the frame having an arm to which the arm of the slidable element is pivoted and a transverse recess to receive the end of the arm when the rock shaft is operated in one direction, whereby the end of the slidable element may be slightly inclined through a portion of its travel to permit the ready entry of the nut to be fractured between the 5 slidable element and the abutment, a tilting cover pivoted to the slidable element, and a cam portion carried by the rock shaft adapted to raise the cover when the rock shaft is actuated in one direction, releasing 10 it when operated in the opposite direction.

5. In a device of the character described, a frame provided with ways to receive and guide a slidable element, the slidable element having a projecting arm integral 20 therewith, a rock shaft journaled in the frame having an arm to which the arm of the slidable element is pivoted, said rock shaft also provided with a transverse recess to receive the arm of the slidable element when the rock shaft is actuated in one 25 direction, means for operating the rock shaft, an adjustable abutment supported by the frame, and a tilting cover pivoted to the arm of the slidable element and means 30 carried by the rock shaft to automatically raise the cover when the rock shaft is operated in one direction, said cover being adapted to close when the rock shaft is operated in the opposite direction.

35. 6. In a device of the character described, a frame adapted to support and guide a slidable element, an adjustable abutment supported in the frame, the slidable element, having a rearwardly extending arm, 40 a rock shaft journaled in the frame having an arm to which the slidable element is pivoted, said rock shaft adapted to admit of the arm of the slidable element being on the same plane with the journals of the rock shaft when the latter is operated in one 45 direction, and a lever to actuate the rock shaft.

7. In a device of the character described, a frame adapted to support and guide a 50 slidable element, an adjustable abutment supported in the frame, the slidable element having a rearwardly extending arm, a rock shaft journaled in the frame having an arm to which the slidable element is pivoted, said rock shaft adapted to admit of the arm of the slidable element being on the same plane with the journals of the rock shaft when the latter is operated in one 55 direction, a lever to actuate the rock shaft, 60 and a cover hinged to the arm of the slidable element adapted to be raised by the rock shaft when the latter is operated in one direction and closed when operated in the opposite direction.

65. 8. In a device of the character described,

a frame adapted to support and guide a slidable element, an adjustable abutment supported in the frame, the slidable element having a rearwardly extending arm, a rock shaft journaled in the frame having 70 an arm to which the slidable element is pivoted, said rock shaft adapted to admit of the arm of the slidable element being on the same plane with the journals of the rock shaft when the latter is operated in one direction, and a lever to actuate the rock shaft, 75 said frame provided with a projecting portion adapted to limit the travel of the lever in one direction.

9. In a device of the class described, a 80 frame, an abutment carried by the frame, a sliding element supported by the frame, and means for first moving the sliding element rectilinearly and for tilting the latter upon the limit of its rectilinear movement 85 in one direction.

10. In a device of the character described, a frame, an abutment carried by the frame, a sliding member carried by the frame, means for imparting a rectilinear reciprocatory movement to the sliding member, and means for tilting the sliding member upon the limit of its rectilinear movement in one 90 direction.

11. In a device of the class described, a 95 frame, an abutment carried by the frame, a sliding element supported by the frame, means including a rock shaft for imparting a rectilinear reciprocatory movement to the sliding member, and means on the rock shaft 100 for permitting a tilting movement of the sliding member at the limit of the movement of the latter in one direction.

12. In a device of the class described, a frame, an abutment carried by the frame, 105 a sliding element supported by the frame, a rock shaft journaled in the frame, an arm secured to the sliding element, means connecting the rock shaft with the arm of the sliding member, a recess in the rock shaft to 110 receive the end of the arm of the sliding member when the rock shaft is turned in one direction whereby the sliding member is tilted, and means for oscillating the rock shaft.

13. In a device of the class described, a 115 frame, an abutment carried by the frame, a sliding member supported by the frame, a rock shaft journaled in the frame, a cover pivotally mounted within the frame, and 120 means on the rock shaft for raising the cover.

14. In a device of the character described, a frame, an abutment, a sliding element supported by the frame, a rock shaft mounted 125 in the frame, means connecting the sliding element with the rock shaft, a cover pivotally mounted on the sliding element, and means carried by the rock shaft for elevating the cover.

15. In a device of the character described, an abutment, a sliding element supported in the frame, a rock shaft mounted in the frame, means connecting the sliding element with the rock shaft, a cover pivotally mounted on the sliding element, means carried by the rock shaft to elevate the cover, said means being so positioned on the rock shaft

as to elevate the cover on the retraction of the sliding element.

In testimony whereof, I sign this specification in the presence of two witnesses.
